UNITED STATES PATENT OFFICE

2,503,940

BUMPER HOLDER FOR FLUSH VALVES

John J. Delany, Brooklyn, N. Y., assignor to
 Delany Realty Corporation, Brooklyn, N. Y., a
 corporation of New York

Application July 26, 1946, Serial No. 686,576

2 Claims. (Cl. 4—248)

1

This invention relates to bumpers providing stop means for limiting the rearward swinging movement of toilet seats and the invention has particular reference to a buffer or bumper of said character adapted to be attached to the flush valve of the toilet installation.

It has been the practice to manufacture flush valves with bumpers for said purpose formed as an integral part of the upper portion of the valve casing. Such construction, however, has the disadvantage that the bumper projecting outwardly beyond the surface of the valve casing renders it difficult to grind and polish the outer face of the valve necessitating a prolonged manual grinding and polishing operation so as to increase the cost thereof. In order to overcome these objections, the present invention provides a holder or mounting adapted to be secured to the top of the flush valve in covering relation with the adjusting screw thereof and to which a bumper is releasably affixed. By this construction the outer surface of the valve body may be readily ground and polished without the inconvenience of an outwardly extending obstruction in the way of the grinding tool and the holder to which the bumper is releasably attached may also be readily ground and polished on the outer peripheral face thereof since the grinding and polishing may be performed before the attachment of the bumper therewith.

The invention further has in view the provision of a holder adapted to engage over the nut of the upper portion of the body of the flush valve and to be secured thereon by the means for attachment of the bumper thereto.

With the foregoing and other objects in view, reference is now made to the following specification and accompanying drawings in which the preferred embodiment of the invention is illustrated.

In the drawings:

Fig. 1 is a view of a flush valve partly in vertical section constructed in accordance with the invention.

Fig. 2 is a horizontal sectional view therethrough taken approximately on line 2—2 of Fig. 1.

Referring to the drawings by characters of reference, the bumper is releasably secured in a holder 10 which is in the form of a cap secured upon the hexagonal shaped extension of the upper portion of a flush valve A. The holder consists of an annular top wall 11 provided with an integral peripheral rim 12 formed with an

outwardly projecting lip 13 extending peripherally about the free edge of the rim.

A plurality of circumferentially spaced inwardly projecting beads 14 are formed on the inner face of the rim 12 which extend from the free edge of the rim to the top wall 11. The rim 12 is also provided with an aperture 15 disposed substantially opposite the beads 14 for receiving therethrough an internally and externally threaded bushing 16 which is formed at its inner end with a flange 17 located within the holder 10 with the threaded portion of the bushing protruding radially through the aperture 15. A screw plug 18 protrudes inwardly through the threaded bore of the bushing 16 into engagement with the hexagonal shaped upper end of the flush valve for securing the holder 10 thereon. The screw plug 18 is formed with a kerf 19 in the outer end thereof for receiving a tool for turning the same so as to impinge the inner end thereof against the hexagonal shaped upper end of the flush valve to thereby position the oppositely disposed angulated portion thereof between adjacent beads 14 with the adjacent faces 25 of the said hexagonal shaped upper end portion bearing against the outer curved surfaces of the beads for preventing relative movement of the holder thereon and for positioning the cap with the bushing 16 projecting outwardly in the desired relation.

In addition to providing means for securing the holder 10 on the flush valve the bushing 16 also provides a mounting for a toilet seat bumper 20. The bumper is of cylindrical formation having 35 a flanged inner end 21 which is arranged within a cap 22 with the outer reduced end of the bumper projecting outwardly through an opening 23 in the end thereof. The cap 22 is internally threaded and is threadedly secured upon the bushing 16 in covering relation with the screw plug 18.

The bumper 20 is preferably composed of compressible resilient material such as natural or synthetic rubber so that the same does not 45 mar the toilet seat when engaged thereagainst, and when so constructed the bumper may be readily replaced when the same becomes worn or damaged.

What is claimed is:

1. In a buffer, a cap adapted for engagement over a polygonal shaped body, said cap including a peripheral wall having a plurality of ribs alternating with depressions on the inner face thereof and formed with an aperture therethrough disposed substantially opposite said ribs, an ex-

ternally and internally threaded flanged bushing protruding through said aperture with the flange thereof disposed against said peripheral wall, a plug threadedly engaged in said bushing and adapted to be tightened against said body for securing the cap thereon with an angulated edge of said body impinged between adjacent ribs, an internally threaded tubular member having a restricted opening in its outer end threadedly engaged over the outer end of said bushing, and a resilient buffer element protruding through said restricted opening in said tubular member and having an enlarged inner end for securing the same within said tubular member.

2. In a buffer, a cap adapted for engagement over a polygonal shaped body, said cap including a peripheral wall having a plurality of peripheral ribs alternating with depressions on the inner face thereof and formed with an aperture therethrough disposed substantially opposite said ribs, a flanged bushing arranged in protruding

relation in said aperture, a screw plug located in the bore of said bushing and adapted to be tightened against said body for securing the cap thereon with an edge of said body impinged between adjacent ribs, a tubular member secured over the outer end of said bushing, and a resilient buffer element having its inner end located in said tubular member with the outer free end thereof protruding therethrough.

JOHN J. DELANY.
